UNITED STATES PATENT OFFICE.

LOUIS SCHULZE, OF PHILADELPHIA, PENNSYLVANIA.

MEDICATED-VAPOR BATH.

SPECIFICATION forming part of Letters Patent No. 280,675, dated July 3, 1883.

Application filed February 6, 1883. (No model.)

To all whom it may concern:

Be it known that I, LOUIS SCHULZE, a citizen of the United States, residing at Philadelphia, in the county of Philadelphia and State of Pennsylvania, have invented certain new and useful Improvements in Medicated-Vapor Baths; and I do hereby declare the following to be a full, clear, and exact description of the invention, such as will enable others skilled in the art to 10 which it appertains to make and use the same.

My invention relates to improvements in that class of vapor-baths in which the medicines are imparted to the body of a patient in a vaporized state after the patient has received 15 a bath of superheated or dry steam, by which the pores of the skin have been opened; and the object is to introduce into the system of patients, especially those afflicted with rheumatism, dropsy, neuralgia, and all other diseases 20 originating from the blood, the medicated vapors mixed with steam in a more thorough and efficient manner than has been heretofore done by appliances known to me.

The invention consists in surrounding the 25 patient with an air-tight covering or casing, made of india-rubber, oil-cloth, or other air-tight material, the lower edges of said covering being inserted in a trough containing water and forming a water-seal, while the upper part 30 is closely tied around the neck of the patient, and in supporting said covering by a suitable frame of wires or tubes. Into the space formed in this covering is introduced the superheated steam from a boiler, and preferably containing 35 salt-water, and after the patient is in complete perspiration introducing the medicines or compounds vaporized in a separate boiler, and allowing them to mingle with the superheated steam.

It also consists of certain details of construction and arrangement of parts, as will be more fully described hereinafter, and more specifically pointed out in the claims, reference being had to the accompanying drawing and 45 the letters of reference marked thereon.

In the drawing the figure represents a sectional elevation representing my invention.

In said drawing, A is a platform of suitable size, provided with an annular gutter or 50 trough, a, for containing water, and forming a water-seal. This platform is covered with

zinc, and upon it is placed a chair or seat, upon which the patient is seated. A covering or casing, B, made of rubber, oil-cloth, or other air-tight material, is then placed around the 55 patient, forming a space around him, and secured in suitable manner around his neck, while the lower edges of the covering are inserted into the trough, so as to prevent the escape of any vapor. A steam-boiler, C, heated 60 in any suitable manner to generate steam, is connected by a pipe, c, to a smaller superheating-boiler, D, by which the steam is thoroughly dried and superheated, and it passes thence through a pipe, d, into the space within the 65 covering. A tight joint is made where the pipe d enters said covering, and is provided with a suitable valve, e. The end of the pipe d within the covering is bent downward, to prevent the steam passing against the body of the 70 patient. The steam in the boiler is generated preferably from sea-water. The medicines or medical compounds which are intended to be applied to the body of the patient are then vaporized in a separate boiler, E, and after the 75 patient has got into a thorough perspiration the medicated vapors are also introduced, by means of a pipe, f, provided with a valve, g, into the space formed by the covering and thoroughly mingled with the superheated steam, 80 and its effects are imparted to the patient. Some of the medicines I employ are sulphur, phosphorus, hartshorn, and lime, although any other medical compounds may be employed 85 in a vaporized state. All the joints must be closely packed. The frame-work is preferably made as small as possible, so as to obviate the necessity of employing too great a quantity of steam or medicated vapors, but still allowing the patient to move freely within it. A thermometer, i, is applied to the covering to indicate the pressure of steam. An outlet-pipe, h, leading preferably outdoors, permits the air contained within the space in the covering to escape, as it is displaced by the steam entering it. 90

Having thus described my invention, what I claim, and desire to secure by Letters Patent, is—

1. The combination of an air-tight covering 100 supported on a suitable frame with a platform provided with a water-trough, into which the

lower ends of the covering dip to form a water-seal, substantially as and for the purpose set forth.

2. The combination of a steam-generating boiler, C, and a superheating-boiler, D, having pipes *e* and *d*, with an air-tight covering, B, surrounding the patient, and a platform, A, provided with a trough, *a*, to form a water-seal, substantially as specified.

10 3. The combination of a steam-generating boiler, C, and a superheating-boiler, D, having pipes *e* and *d*, with a boiler, E, for generating medicated vapors, and an air-tight covering, B, surrounding the patient, substantially as 15 and for the purpose set forth.

4. The combination of a steam-generating boiler, C, and a superheating-boiler, D, having pipes *e* *d*, with a boiler, E, for generating medicated vapors, an air-tight covering, B, surrounding the patient and arranged to be 20 inserted into a water-trough, *a*, on the platform A, substantially as specified.

In testimony whereof I hereby affix my signature in presence of two witnesses.

LOUIS SCHULZE.
